UNITED STATES PATENT OFFICE.

SAMUEL J. SHERER, OF CHICAGO, ILLINOIS.

DESIGN FOR A DISPLAY-COUNTER.

SPECIFICATION forming part of Design No. 25,328, dated March 31, 1896.

Application filed February 15, 1896. Serial No. 579,456. Term of patent 7 years.

To all whom it may concern:

Be it known that I, SAMUEL J. SHERER, a citizen of the United States, and a resident of Chicago, in the county of Cook and State 5 of Illinois, have invented and produced a new and original Design for Display-Counters, of which the following is a specification, reference being had to the accompanying drawing, showing a part thereof.

10 This design relates to counters for exhibition, storage, and other purposes, and has for its object to produce a novel and ornamental counter which shall present to the eye a distinguishing and characteristic appearance.

15 The leading feature of my design consists in a casing of oblong rectangular form having a flat top with rounded edges, solid or paneled end walls, and divided into drawer-sections extending from rear to front, the two 20 upper tiers presenting a vertical front, while the bottom of the casing is projected in front and the faces of the lower tier slant backward and upward to meet the vertical of the upper tiers and form an obtuse angle there- 25 with. The sections thus formed, being surrounded by a frame or beading, are provided with drawers having front end walls corresponding in size and shape to the said sections and to their front opening. The whole 30 is mounted upon a solid base grooved and beaded longitudinally.

The design is illustrated in the accompanying drawing, in which the figure represents a perspective view of a counter embodying the design.

In said drawing A designates the body portion or casing of the counter, this casing being of oblong rectangular form in front and rear elevations. The top of the counter B is flat and has rounded edges which project beyond the front and ends of the body portion. The front of the casing A is divided into a series of rectangular drawer-sections C and D disposed in horizontal tiers, the upper sections C presenting a vertical front, while the 40 lower sections D have an upward and backward slant by reason of the projecting bottom and lower front of the ends. Drawers E and F provided with front end walls *a* and a molding *b* fit into these drawer-sections, and 45 a grooved frame or beading *c* surrounds and overlaps the sections C and D, the whole being supported by the substantial base II having its outer surfaces raised and grooved longitudinally.
